UNITED STATES PATENT OFFICE.

VENTRY R. HISEY AND EARL R. FINCH, OF WAYNE, MICHIGAN.

COMBINATION TABLE AND BENCH.

Application filed August 30, 1923. Serial No. 660,157.

This invention relates to a combined table and bench, and the primary object of our invention is to furnish a table with benches or seats that may be swung from active positions at the sides of the table to inactive positions under the table top so that the benches will be out of the road, permit of the table being used for various purposes, and yet have the benches accessible for seats at the sides of the table.

Another object of our invention is to furnish a table with swingable benches or seats which are articulated with the table to at all times remain in vertical or upright positions while being swung from active to inactive positions or vice versa. The articulation of the benches and tables is such as not to interfere with the feet of persons occupying the benches or seats, not materially obstruct the passage between the table and benches, and not detract from the appearance of the table.

A further object of our invention is to provide a new piece of furniture embodying a table with shiftable benches attached thereto, and said benches are provided with foldable leg sections that may be swung inwardly, when the benches are in inactive positions, so that there will be no protruding bench portions to interfere with the general appearance or exterior contour of the table.

The above are a few of the objects attained by our combined table and bench and reference will now be had to the drawing, wherein

Figure 1 is an end view of the table showing one of the benches in an active position and the other in an inactive position;

Fig. 2 is a side elevation of a portion of the table with the bench in an active position;

Fig. 3 is a similar view showing the bench in an inactive position;

Fig. 4 is a plan of a portion of the table and bench as shown in Fig. 2, and

Fig. 5 is a plan of a portion of the table as shown in Fig. 3.

Considering the construction of the table, we provide a table top 1 supported by end frames or legs 2 having feet 3 connected by a longitudinal tie member 4. The upper ends of the supports or legs 2 are also connected by a longitudinal tie member 5, under the table top 1, serving as a bench stop or abutment.

The table is oblong and at the sides thereof are benches adapted to rest on the same floor as the table and adapted to be swung upwardly under the table top so as to be out of the road. The benches are identical in construction therefore we deem it only necessary to describe the detail construction of one of said benches.

Each bench comprises a top or seat 6 having fixed end supports or legs 7 and swingable supports or legs 8 which are hinged or otherwise pivotally connected to the vertical edges of the fixed end supports or legs 7, so that the supports or legs 8 may be swung inwardly at a right angle to the supports or legs 7 and occupy a position approximately in the central vertical plane of the bench, when in an inactive position, otherwise the swingable supports or legs 8 are in the same transverse plane as the supports or legs 7.

The upper ends of the fixed supports or legs 7 are braced relative to the lower face of the top or seat 6 by brackets 10 and adjacent the lower ends of said supports or legs 7 is a longitudinal tie member 11. The lower ends of the supports or legs 7 and 8 terminate in feet 12 and the feet of the supports or legs 7 are connected to the feet 3 of the table by sets of parallelized links 13 and 14 which have the ends thereof pivotally connected to the feet 3 and 12 by pivot bolts 15 or other pivotal means. The links 13 and 14 have the pivots thereof off-set relative to each other, as best shown in Fig. 1, the pivots of the link 14 being in a plane below the pivots of the links 13 and the last mentioned links are of such configuration that the intermediate portions of the links 13, between the bench and the table, will be in the same horizontal plane as the links 14 so as to avoid any high obstruction between the bench and the table over which a person might stumble when taking a seat at the table.

By using two sets of links with the bench of less length than the table the bench may be bodily raised and swung under the table top 1 until it impinges against the stop or abutment 5. During this adjustment of the bench the linkage due to its parallel motion maintains the bench constantly vertical and after the bench has been placed under the table top the swingable supports or legs 8 may be swung inwardly, as shown in Fig. 3, so as to be wholly between the end legs or

supports 2 of the table and thus not interfere with a person moving between the table and bench.

It is obvious that our piece of furniture 5 may be used for various purposes, may be finished to one's esthetic taste, and may simply have a single bench instead of two. We reserve the right to make such other changes as are permissible by the appended claim.

10 What we claim is:—

A nestable seat and table comprising, in combination, a table and a seat each comprising a top and floor engaging supports, a pair of always parallel rigid links, said links being pivotally connected by fixed pivots at their ends, to the table, and seat sup-

ports adjacent the floor engaging portions thereof and the portions of the said links between the said table and seat lying closely adjacent each other and to the floor when 20 the said seat is in position of use, the said links enabling the said seat to be swung to a position with its top under and parallel with the table top, and a stop member located on the table structure in a position to 25 check the movement of the seat structure after the links have passed the vertical.

In testimony whereof we affix our signatures.

VENTRY R. HISEY.
EARL R. FINCH.
